ABE GRUBER,
INVENTOR,

BY
Victor M. Hefland
ATTORNEY

UNITED STATES PATENT OFFICE

147,173

DESIGN FOR A RAINCOAT OR SIMILAR ARTICLE

Abe Gruber, New York, N. Y.

Application December 9, 1946, Serial No. 135,370

Term of patent 3½ years

(Cl. D3—4)

To all whom it may concern:

Be it known that I, Abe Gruber, a citizen of the United States of America, residing in New York city, county of New York, and State of New York, have invented a new, original, and ornamental Design for a Raincoat or Similar Article, of which the following is a specification, reference being had to the accompanying drawing, forming part thereof, wherein,

I claim:

The ornamental design for a raincoat or similar article, substantially as shown.

ABE GRUBER.
